(57) CLAIM

I claim the ornamental design for an ice cream scoop, as shown.

DESCRIPTION

FIG. 1 is a front perspective view of the ice cream scoop showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is an inverted right side elevational view thereof.
